UNITED STATES PATENT OFFICE.

LE GRAND SKINNER, OF ERIE, PENNSYLVANIA.

STEAM-ENGINE.

1,159,112.

Specification of Letters Patent.

Patented Nov. 2, 1915.

Application filed March 25, 1914. Serial No. 827,109.

To all whom it may concern:

Be it known that I, LE GRAND SKINNER, a citizen of the United States, residing at Erie, in the county of Erie and State of Pennsylvania, have invented certain new and useful Improvements in Steam-Engines, of which the following is a specification.

This invention relates to that type of engines known as "uniflow" engines in which the steam travels in only one direction from admission to exhaust. Ordinarily, in such engines, the steam enters the cylinder at the ends, and, after cut-off and expansion have taken place, is exhausted at the end of the stroke through exhaust ports arranged around the middle of the cylinder, which ports are uncovered by the piston, which thus operates as an exhaust valve. The steam, consequently, flows in but one direction, that is, from the ends of the cylinder toward the middle. Or it may enter the cylinder at the middle, and exhaust at the ends. These engines usually operate condensing, but to preserve the uniflow effect and at the same time to be able to operate non-condensing with small clearances, the Skinner-Williams Patent No. 1,033,280 disclosed an engine of the uniflow type which, in addition to the central exhaust ports, is provided with additional exhaust valves located between the central exhaust ports and the ends of the cylinder, which additional or auxiliary valves are operated to remain open, after the exhaust ports are closed by the passage of the piston thereover, whereby heavy compression, when running non-condensing, is prevented and the engine is available for non-condensing use. In the engine disclosed in said patent, the auxiliary exhaust ports are in communication with the exhaust pipe or passage leading from the middle exhaust ports, and accordingly one pipe or passage takes care of the exhaust from all the ports.

The object of the present invention is to make possible the exhausting of the steam from the cylinder through the middle exhaust ports into an exhaust pipe at atmospheric pressure, or against the usual back pressure in a heating system, whereby such exhaust steam may be utilized for heating or other purposes, and at the same time, or as soon as the piston has covered the central exhaust ports on the compression stroke, the auxiliary exhaust valves are opened to communicate through pas-

sages to a condenser, the object being to utilize the steam exhausted from the central exhaust ports for heating or other purposes, and at the same time obtain added economy due to operating the engine with the atmospheric pressure removed during part of the compression or return stroke.

The exhaust through the auxiliary exhaust ports is separated from that passing through the main or middle exhaust ports; and the engine may be, therefore, operated as a non-condensing engine so far as exhausting the steam at atmospheric or heating pressure through the central exhaust ports is concerned, and as a condensing engine by exhausting into a condenser the vapor remaining in the cylinder after the piston has covered the central exhaust ports on the compression or return stroke, and so timing the opening of the auxiliary exhaust valves that they will not open until the piston on the return or compression stroke has covered the middle exhaust ports, and so timing the closing of the auxiliary exhaust valves that they will close shortly after the piston has covered the auxiliary exhaust port on that side, or at such point as to give suitable compression.

A modification is provided by means of which the engine can operate entirely as a condensing engine, as might be advisable where exhaust steam is not needed for other purposes, as in the summer, by means of connections controlled by valves between the middle exhaust ports and the auxiliary exhaust ports, or connected to a condenser.

It will be seen that, by separating the two exhausts, when release takes place the whole volume of steam is available for heating purposes, without withdrawal of pressure from the pressure side of the cylinder, still maintaining, if desired, proper vacuum on the exhaust side of the piston, by means of the auxiliary exhaust ports connected to the condenser. Practically all of the steam in the cylinder at pressure of release escapes through the middle ports, when they are uncovered by the piston, while the few pounds remaining in the cylinder at atmospheric or heating pressure are withdrawn through the auxiliary exhaust valves to the condenser.

An embodiment of the invention is illustrated in the accompanying drawing, in which:—

Figure 1 is a longitudinal section of the

cylinder. Fig. 2 is a side elevation, partly in section, of a modification in which valved passages are provided to connect all the exhaust ports when desired. Fig. 3 is an end elevation of Fig. 2. Fig. 4 represents a combined indicator diagram, where the unshaded portion is the card that would be obtained from a non-condensing uniflow or central exhaust engine. The cross-hatched portion represents the additional area secured by operating this engine utilizing the exhaust from the central port, and condensing the residual as illustrated in Fig. 1 and hereinafter described. Fig. 5 represents an indicator diagram from a condensing uniflow or central exhaust engine, where all the exhaust is led to the condenser as hereinafter described with reference to the modification illustrated in Figs. 2 and 3.

20 Referring specifically to the drawing, 6 indicates the cylinder, 7 the piston, 8 the middle or main exhaust ports and 9 the inlet ports, the inlet valves being omitted. 10 is the piston rod.

25 The middle exhaust ports communicate with an annular passage 11 leading to a main exhaust pipe 12 which may be extended to a heating apparatus or to other places where low pressure steam may be utilized, 30 as for heating feed water or the like.

The auxiliary exhaust ports 13 are preferably located between the middle exhaust ports and the ends of the cylinder, preferably in substantially the same relation or 35 position as that described in the patent above referred to, but could be located elsewhere. The passages leading from these ports are separated from the main exhaust passage by walls 14 and are connected by 40 branch pipes 15 to an auxiliary exhaust pipe 16 which will or may be connected to a condenser (not shown). The auxiliary exhaust passages are controlled by puppet valves 17 which may be operated by any suitable valve 45 gear (not shown), contained in the casings 18. The particular mechanism for operating the auxiliary exhaust valves is immaterial.

In operation, when the piston uncovers the 50 middle exhaust ports 8 practically a full exhaust takes place, the steam conducted through the pipe 12 being available for heating or other purposes. The auxiliary exhaust valve remains closed during the expansion period and until the piston, on the 55 return stroke, covers the ports 8, when compression would begin, but the auxiliary exhaust valve is then opened, permitting remaining or additional exhaust through the auxiliary exhaust ports 13 at that end of the 60 cylinder, to the condenser, under such vacuum as may be maintained. After the piston covers the auxiliary exhaust ports 13, the valve may be closed; but under certain conditions it may be advisable, and in any event it is possible, and within the scope of

the invention, to close the auxiliary valve before the piston covers said port. Necessarily, if the auxiliary valves are located where the piston would not operate to close said ports, the ports would be controlled 70 solely by the valves. On the next stroke the same operation is effected at the other end of the cylinder, in a double-acting engine.

It will be seen that all the steam is withdrawn from the exhaust side of the piston, 75 and none from the pressure side, so there is no loss of pressure and full economy of steam is preserved, and a relatively small condenser may be used, since it has to take care only of the residual steam remaining 80 after the main exhaust.

The engine will give a diagram showing a drop to atmosphere, or substantially so, following the opening of the main exhaust ports, and a further drop to vacuum following the opening of the auxiliary exhaust port which opens communication to the condenser. The increased area of such a diagram, as shown in cross-hatched diagram, Fig. 4, indicates an increased effect of pressure with the same amount of steam supply, with of course increased indicated horse power and increased economy over the non-condensing engine. But if the steam exhausting through ports 8 is not needed for other purposes, the engine may be operated full condensing by the modification shown in Figs. 2 and 3 in which a connection 24 is provided between the main exhaust pipe 12 and the auxiliary exhaust pipe 16, said connection having a valve 25, which when opened will connect all the exhaust passages to the condenser, another valve 26 being placed in the exhaust pipe 12, beyond the cross connection referred to, which valve 90 when closed will cut off the communication from the middle exhaust to the atmosphere or heating apparatus.

The engine may be operated full non-condensing by closing valve 27 in exhaust line 110 16 to condenser, and opening valves 25 and 26.

I claim—

1. A uniflow engine cylinder having a middle exhaust port and auxiliary exhaust 115 ports toward the ends of the cylinder, the middle port being connected to pressure-containing devices, and the auxiliary ports being connected to a condenser, and valves controlling the auxiliary ports and timed to remain closed during the expansion period and to open after the middle port has been closed on the exhaust stroke.

2. A uniflow engine cylinder having a middle exhaust port connected to a heating 125 system, and valved auxiliary ports located between the said middle port and the ends of the cylinder and connected to a condenser.

3. A steam engine cylinder having a mid- 130

idle exhaust port and a conduit therefrom to devices receiving steam at low pressure, and auxiliary ports located between the middle port and the ends of the cylinder, a conduit leading from said auxiliary ports to a condenser, and a valved cross connection between said conduits.

4. A steam engine having a middle exhaust port and auxiliary exhaust ports located between the middle port and the ends of the cylinder, and a casing extending along the cylinder and having a middle exhaust passage communicating with the middle port and adapted for connection to a heating system or the like, and also having separate auxiliary exhaust passages at the ends communicating with said auxiliary ports and adapted for connection to a condenser, and valves located in said auxiliary passages and controlling the same.

5. A steam engine having a main exhaust port and valved auxiliary exhaust ports, means for delivering steam from the main port to a heating or other low pressure system, at the end of the power stroke, and means for withdrawing residual steam separately at a lower pressure through the auxiliary ports after the main port is closed, on the exhaust or return stroke.

6. A reciprocating steam engine of the type having a main exhaust port and auxiliary exhaust ports between the main port and the ends of the cylinder, means for exhausting the steam through the main port at the end of the power stroke of the piston, against atmospheric or other low pressure and then closing said port and means for holding the auxiliary port closed during the power stroke, and then exhausting the residual steam through the auxiliary port, under vacuum, during the return stroke of the piston.

7. An engine cylinder having a main exhaust port connected to a pressure-containing system, the opening and closing of said port being effected by movement of the piston, and having a valved auxiliary exhaust port connected to a condenser.

8. A reciprocating steam engine having a main exhaust port, controlled by the piston, and auxiliary exhaust ports, and means for exhausting residual steam through an auxiliary exhaust port to a condenser, after the piston has covered the main exhaust port on the return stroke.

9. A steam engine having main and auxiliary exhaust ports, means for exhausting steam through the main exhaust port after expansion on the power stroke, and means for exhausting residual steam through an auxiliary port to a condenser on the return stroke.

10. A steam engine having main and auxiliary exhaust ports, means for exhausting steam through the main exhaust port at a certain pressure, at the latter part of the power stroke, and means for exhausting residual steam through an auxiliary port on the return stroke, at a lower pressure than the exhaust through the main port.

11. A reciprocating steam engine provided with means for exhausting steam therefrom at a certain pressure at the end of the power stroke of the piston and means for exhausting residual steam therefrom at a lower pressure, on the return stroke of the piston.

In testimony whereof, I affix my signature in presence of two witnesses.
